UNITED STATES PATENT OFFICE.

EDWARD A. FARR, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR AN ARTICLE OF MANUFACTURE.

47,379.

Specification for Design.

Patented May 25, 1915.

Application filed October 23, 1914. Serial No. 868,341. Term of patent 7 years.

To all whom it may concern:

Be it known that I, EDWARD A. FARR, a citizen of the United States, residing at Meriden, New Haven county, Connecticut, have invented a new, original, and ornamental Design for an Article of Manufacture, of which the following is a specification, reference being had to the accompanying drawing, forming a part thereof, in which the figure is a plan view of my new

design to be applied to an article of manufacture.

I claim:

The ornamental design for an article of manufacture or plate as shown.

EDWARD A. FARR.
